EGG CLEANER

Neil E. Bridgman, Sunnyside, Wash.

Application August 21, 1935, Serial No. 37,239

2 Claims. (Cl. 51—190)

This invention appertains to new and useful improvements in cleaning devices and more particularly to a device especially adapted for cleaning eggs. The principle object of the present invention is to provide a cleaner whereby eggs can be cleaned quickly and thoroughly without injuring the shells thereof.

Another important object of the invention is to provide an egg cleaner wherein the cleaning elements can be readily removed for the purpose of repair or replacement thereof.

Other important objects and advantages of the invention will become apparent to the reader of the following specification.

15 In the drawings

Figure 1 represents a side elevational view of the machine.

Figure 2 represents a fragmentary vertical sectional view through the machine.

20 Figure 3 represents a cross sectional view taken substantially on the line 3—3 of Figure 1.

Figure 4 represents a perspective view of one of the flaps.

25 Figure 5 represents a side elevational view of the mandrel.

Figure 6 represents a sectional view through one of the mandrel pins showing one of the flaps thereon.

Referring to the drawings wherein like numerals designate like forms, it can be seen that numeral 5 represents the electric motor from which extends the armature shaft 6. The novel cleaner is generally referred to by numeral 7 and consists of a mandrel shown in Figure 5. The 30 mandrel consists of the hub 8 having a circumferentially extending flange 9 thereon and a set screw 10 whereby the hub is secured to the armature shaft 6 substantially in the manner shown in Figure 2.

40 The flange 9 is provided with a plurality of circumferentially arranged end openings 11. Numerals 12—13 represent a pair of disks which at their central portions are provided with annular arrangements of openings 14. A plurality of pins 15 extend through the openings 14 of the disks 12—13 and each is provided with a head 16 at one end while its opposite end is engaged into a corresponding opening 11 of the hub flange 9.

45 It is to be understood, that the pins 15 are suitably secured, as by soldering, to the flange 9, and with the assembly as shown in Figure 2, all that is required to replace the flaps 18 is to first remove the split ring 17 so that the sheet rubber disk 13 can be slipped over the heads 16 of the pins and the flaps 18 subsequently removed over the headed ends of the pins. The clips 19 serve to hold the flaps in place on the ring when the strips 18 of the flaps are properly placed on the 50 pins.

5 It can now be seen, that when the motor 5 is set in operation the mandrel will rotate and the flap formed by the emery cloth clipped on the pins 15 will lie between the disks 12—13 and when an egg or similar article is held in the path of the flaps it will be cleaned off very quickly and thoroughly.

It can be seen that the clip 19 can be easily removed to renew the flap and that the pins 15 can be readily removed to dismantle the mandrel for the purpose of repair or replacement of parts.

While the foregoing specification sets forth the invention in specific terms, it is to be understood that numerous changes in the shape, size 15 and materials may be resorted to without departing from the spirit and scope of the invention as claimed hereinafter.

Having described the invention, what is claimed as new is:

20 1. A cleaner of the character described comprising a rotary shaft, a hub on the shaft provided with a plurality of annularly arranged openings, a plurality of pins extending from the hub and each having one end engaged into a corresponding opening in the hub, the outer ends of the said pins being provided with heads, a disk provided with openings therein for receiving the pins and being disposed against the hub, a second disk having openings therein for receiving 25 the pins and being disposed on the outer ends of the pins, flap members having hems through which the pins are disposed, the last mentioned disk being of elastic material so that it can be pulled over the heads of the pins so that the said 30 flaps can be displaced from the pins.

2. A cleaner of the character described comprising a rotary shaft, a hub on the shaft provided with a plurality of annularly arranged openings, a plurality of pins extending from the 40 hub and each having one end engaged into a corresponding opening in the hub, the outer ends of the said pins being provided with heads, a disk provided with openings therein for receiving the pins and being disposed against the hub, a second disk having openings therein for receiving 45 the pins and being disposed on the outer ends of the pins, flap members having hems through which the pins are disposed, the last mentioned 50 disk being of elastic material so that it can be pulled over the heads of the pins so that the said flaps can be displaced from the pins, and an annular member of resilient material for engagement around the pins adjacent the ends thereof 55 to prevent displacement of the last mentioned disk.

NEIL E. BRIDGMAN.
